UNITED STATES PATENT OFFICE.

ANTON K. KUSEBAUCH, OF PITTSBURGH, PENNSYLVANIA, ASSIGNOR TO LOCOMOTIVE STOKER COMPANY, OF PITTSBURGH, PENNSYLVANIA, A CORPORATION OF PENNSYLVANIA.

LOCOMOTIVE DRAFT APPLIANCE.

1,356,824.

Specification of Letters Patent. Patented Oct. 26, 1920.

Application filed March 10, 1919. Serial No. 281,714.

To all whom it may concern:

Be it known that I, A. K. KUSEBAUCH, a citizen of the United States, residing in Pittsburgh, county of Allegheny, and State 5 of Pennsylvania, have invented certain new and useful Improvements in Locomotive Draft Appliances, of which the following is a specification.

This invention relates to locomotive draft 10 appliances and particularly to that type comprising a blower fan operated by steam turbine or other form of motor means.

It has for one of its primary objects the provision of improved means for cooling 15 the driving shaft and bearings, an improvement particularly useful either where the whole appliance is placed entirely within the smoke box or where the motor is located exteriorly of the smoke box, with the driving 20 shaft extending into the interior thereof and supported by bearings.

My invention also contemplates the provision of a simple and compact arrangement of draft appliance provided with improved 25 means for maintaining a circulation of cooling fluid therethrough.

I obtain the foregoing, together with such other objects as may hereinafter appear, by means of a construction which I have 30 illustrated in preferred form in the accompanying drawings, wherein—

Figure 1 is a longitudinal section through a locomotive smoke box showing the application of my improvements; and Fig. 2 is a 35 longitudinal section through the draft appliance drawn on an enlarged scale to more clearly illustrate the parts.

Referring now to the drawings, the smoke box is indicated as a whole by the reference 40 letter A, and the draft appliance comprises a blower fan 7, a steam turbine or other form of motor 8, and a driving shaft 9. As shown, the draft appliance is located entirely within the smoke box. The blower 45 fan operates in the usual manner drawing the products of combustion from the fire box through the flues into the smoke box, from which they exhaust through the stack 10. The steam turbine also operates in the 50 usual manner, exhaust steam being supplied to the interior thereof through the passageway 11, the steam being conveyed to such passageway by a pipe 12 or other suitable connection, diagrammatically illustrated in 55 Fig. 1. After passing through the turbine

the steam exhausts through the outlet 13 into the smoke box.

The turbine comprises a cylindrical shell or casing 14 within which revolves the drum 15 carried on the shaft 9. The front end of 60 the casing 14 is closed by the head 16 carrying a housing 17, in which is mounted the front bearing 18 for the shaft 9, the said head being spaced away from the drum 15 so as to provide a balancing chamber 19. The 65 interior of the housing 17 opens into chamber 19. The drum 15 has a loose fit in the casing 14 so as to provide an annular clearance space 20 connecting chamber 19 with the steam space of the turbine. The rear 70 end of the casing 14 is closed by a head 21 from which the rear bearing 22 of the shaft 9 is supported by means of brackets 23.

The parts are cooled as follows:

The shaft 9 is provided with a central 75 aperture or opening 24, such opening extending entirely through the shaft and establishing communication between the housing 17 and the suction space in the interior of the blower fan 7, steam entering the 80 chamber 19 through the clearance space 20 partially condenses, and when such chamber is filled or partially filled with saturated steam, the suction produced by the fan in normal operation will draw a small stream 85 of steam or water through the aperture 24, thus cooling the shaft and its bearings. The fluid thus drawn through the shaft is carried with the products of combustion and is discharged therewith. The front bearing is 90 also exteriorly cooled by any water that may collect in chamber 19 and in the interior of the housing 17. Fluid will be drawn through in volumes sufficient to adequately cool the shaft and its parts, and the exhaust 95 steam particularly after it has been delivered to the turbine, will practically become saturated or tend to condense very rapidly.

In order to assist in cooling the rear end 100 of the shaft adjacent to the bearing 22, which portion of the shaft is nearest the hottest place, I provide the shaft with a plurality of radiating flanges or fins 25.

It will be seen from the foregoing that I 105 have provided a simple arrangement for cooling the shaft and its bearings, which requires no extra parts and utilizes the suction created by operating the fan for maintaining the circulation of cooling fluid. The 110

life of the apparatus is greatly extended and the cooling arrangement is of such character as to lend compactness and simplicity to the whole appliance.

5 **I claim:**

1. A locomotive draft appliance comprising in combination a blower fan, a fluid actuated motor for operating the fan, a shaft, and means whereby the suction of the 10 fan creates a flow of the actuating fluid along the shaft to cool the same.

2. A locomotive draft appliance comprising in combination a blower means, a motor for operating the same utilizing exhaust 15 steam, and a chamber for supplying fluid through the shaft for cooling purposes.

3. A locomotive draft appliance comprising in combination a blower means, a motor utilizing exhaust steam for operating the blower, a hollow shaft, a chamber for holding steam with which the hollow shaft communicates, and means for passing cooling fluid through the shaft. 20

4. A locomotive draft appliance comprising in combination a blower means, a steam actuated motor for operating the blower, a hollow shaft, and means for passing cooling fluid from the source of steam supply for the motor through said hollow shaft. 25

In testimony whereof I have hereunto signed my name.

ANTON K. KUSEBAUCH.
